TENNIS RACKET

Isaac Lee Rosenbalm, Inglewood, Calif.

Application February 14, 1947, Serial No. 728,647

3 Claims. (Cl. 273—73)

1

My invention relates to tennis rackets and has among its salient objects to provide a tennis racket the handle and frame of which is light metal, the construction and arrangement being such that the strings are yieldingly anchored in the loop portion of the frame whereby to have a resiliency which is different from the anchorage of the strings in a solid frame in the usual manner; to provide in a tennis racket a construction in which the ends of the loop portion of the frame are anchored in the opposite sides of the handle and are secured in place therein, thus making an attractive, strong and economical racket frame; to provide in a racket of the character referred to means for tightening a segment of the loop and thus tightening a relatively large portion of the strings.

In order to explain my invention, I have shown the same on the accompanying sheet of drawings in which:

Figure 1 is a face view of a tennis racket embodying my invention;

Figure 2 is an edge view thereof;

Figure 3 is a cross sectional view taken on the line 3—3 of Fig. 1;

Figure 4 is a detail in section, taken on the line 4—4 of Fig. 3;

Figure 5 is a cross sectional view taken on line 5—5 of Fig. 1;

Figure 6 is a similar view taken on line 6—6 of Fig. 1, said sectional views being enlarged for clearness;

Figure 7 is a fragmentary view, partly in section, at the juncture of the loop of the frame with the handle;

Figure 8 is a sectional detail on the line 8—8 of Fig. 7; and

Figure 9 shows how the ends of the bridge portion of the loop, can be formed to fit into the opposite sides of the loop frame.

Referring now in detail to the drawings, my invention as here shown is made of metal, sufficiently light and strong to give as good or better results and satisfaction as rackets made of wood.

The loop of the frame, designated 10 is of light tubular metal, having its two ends, designated 11, 11, inserted into the opposite sides of a handle, designated as a whole 12, with a rivet 13, through said ends and said handle, as shown, and as seen in the sectional view in Fig. 3. Said handle is shown with its opposite sides inturned for a portion of its length, as at 14, 14, so as to expose the ends of the loop at 11, 11, while the opposite sides of said handle, at right angles to the cut away sides, are shown formed with longi-

tudinally extending channels 12', 12' of shallow construction to give finish and also to provide convenient gripping portions for the hands of the player. The end of the handle can be finished as desired, and is shown provided with a finishing cap 15. The cross sectional form of the handle, with the ends of the loop therein, is clearly illustrated in the sectional views in Figs. 3, 5 and 6.

As a means for attaching and anchoring the strings of the racket, I have provided a special anchoring head, designated 16, with a hole therethrough and having a neck portion 16', as seen in Fig. 8, also in Fig. 7. The strings are designated 17 and are shown threaded through these heads 16, with the neck portions inserted into the tubular loop of the frame, as seen in Figs. 7 and 8, with a wire 18 threaded through said neck portions, within the tubular frame, as clearly illustrated. Thus said strings are anchored to the loop by means of this special anchoring head, and it is yieldingly held through the openings provided in the inner face of said loop, and slightly larger than the neck portion so as to permit a slight yielding movement of the head relative to the tubular loop of the racket.

A bridge or connection segment 19 is shown fitted between the opposite sides of the loop as they approach the handle, the opposite ends of said segment 19, being indicated in Fig. 9, and shown inserted through suitable slots 20, in the inner faces of the loop, as seen in Fig. 7. A bolt 21, having a threaded nut 22, is attached to said segment, as shown in Fig. 7, and at its other end attached to rivet 13.

The anchoring heads in the segment or bridge 19, are designated 16'', 16'' and the wire for holding them in place, is designated 18', as clearly indicated in the fragmentary view in Fig. 7.

The anchoring heads 16 and 16'' are of such length to properly space the string, as will be clear, and they can be of such thickness as to lie well within the loop and not protrude at either side of the loop.

Thus I have provided an improved tennis racket which has all the advantages of a wooden racket, and which is light, strong and capable of adjustments to tighten the strings and keep them in good taut condition, and yet provide sufficient resiliency in the means of anchoring them to the frame.

I do not limit my invention to the details of construction and arrangement here shown for explanatory purposes, except as I may be limited by the hereto appended claims.

I claim:

1. A tennis racket having its loop portion formed of tubular material with spaced openings around the inner side thereof, and means for anchoring strings thereto, said means including a series of heads with holes therethrough, each head having a neck portion inserted through one of said openings in the inner face of said tubular loop, strings threaded through said heads across said loop portion, said neck portions each having a hole therethrough, within the tubular loop, and an anchoring wire threaded through said neck portions within said tubular loop to yieldingly anchor said anchoring means.

2. A tennis racket having its loop portion formed of tubular metal with holes through its inner face, means for anchoring strings thereto, said means including a series of heads each having a neck portion to be inserted loosely through the holes in the inner face of said loop, said heads and said neck portions having holes therethrough, an anchoring wire through the holes in said neck portions within said tubular loop portion, for yieldingly anchoring said heads to said loop, and strings threaded through said heads across said loop in opposite directions, said heads being spaced substantially equal to the length of each and spacing said strings threaded therethrough, substantially as illustrated.

3. A tennis racket having a loop portion

formed of tubular metal with its ends converging and extending a distance in substantially parallel relationship, a handle into which said ends telescope for a portion of the length thereof, means securing said ends and said handle together, said handle having opposite sides open to expose said loop ends therein, means for anchoring strings across said loop and including a series of heads having neck portions inserted into said loop portion, said strings being threaded through said heads, and an anchoring wire through the neck portions, within said loop portion, for anchoring said heads to said loop portion, substantially in the manner indicated.
